UNITED STATES PATENT OFFICE.

JESSE LEE LYLE AND JOSEPH FRANK BROOM, OF DANVILLE, VIRGINIA.

BUNCH-BUILDER.

1,362,711.

Specification of Letters Patent. Patented Dec. 21, 1920.

Application filed June 24, 1920. Serial No. 391,331.

To all whom it may concern:

Be it known that we, JESSE L. LYLE and JOSEPH FRANK BROOM, citizens of the United States, residing at Danville, in the county of Pittsylvania, State of Virginia, have invented a new and useful Bunch-Builder, of which the following is a specification.

This invention relates to bunch builders utilized for controlling the quantity of yarn left on quills from automatic looms. One of the objects of the invention is to reduce waste of yarn by insuring the proper construction of a short bunch of yarn at the base of the quill instead of allowing the spinning frame to build the yarn onto the quill with the full stroke from the start of the operation.

A further object is to provide a bunch builder which can be applied to any spinning frame making filling for automatic looms and which device has improved means for automatically controlling the length and depth of the bunch.

Another object is to provide an improved means for changing the ring-rail connection from the bunch builder chain to the main builder chain.

A still further object is to provide a simple and compact structure capable of minute adjustment and having its wearing parts strong and durable.

With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a top plan view of the bunch builder.

Fig. 2 is a side elevation thereof.

Fig. 3 is an end elevation.

Fig. 4 is a detail view of the trip.

Referring to the figures by characters of reference 1 designates a main bearing axle which serves to connect the present improvements with the base of a spinning frame, holding the mechanism in such posi-

tion that the eccentric (not shown) and which is mounted on a shaft of the spinning frame will come into contact with a roller 2 projecting laterally from the body portion 3 of the device and journaled in a bracket 4. The eccentric of the spinning frame and which is above referred to is adapted, by engaging the roller 2, to impart an oscillating motion to the body 3 and the parts connected thereto in a vertical plane about the axis of the shaft or axle 1. An arm 5 is extended from the body 3 of the machine and carries an adjustable counterbalance 6 whereby the machine is held in proper balance during the oscillation mentioned.

A take-up rod 7 is fastened by means of a bracket 8 and bolt 9 to a stationary part of the spinning frame (not shown) and this rod is connected by a turn buckle 10 to a lower rod section 11 which, in turn, is pivotally connected to a rocker arm 12 mounted for oscillation on a longitudinal shaft 13. This shaft is journaled in suitable bearings 14 extending from the body 3 and is provided, near one end, with a worm 15 while secured to the other end portion of the shaft is a ratchet wheel 16. A pawl 17 is pivotally mounted on the arm 12 and is provided with a weighted arm 18 which serves to hold the pawl normally in engagement with the ratchet wheel.

The worm 15 constantly meshes with a worm gear 19 which is formed with or connected to the driver 20 of the main builder chain 21 and also to the driver 22 of the bunch builder chain 23. These drivers can be in the form of drums to which the chains are suitably connected.

A trip 24 is pivotally mounted on a bracket 25 extending from the body 3 and has a longitudinally slotted arm 26 in which is adjustably mounted one end of a connecting rod 27 pivotally attached to a radial arm 28 extending from the driver or drum 22. The trip 24 has an inclined face 29 adapted to be engaged by a trip release 30. A roller 31 is adjustably mounted in a slot 32 and is engaged by the chain 23, this roller being provided for regulating the length of the bunch.

When the machine is set in motion the release 30 engages the inclined face 29. As the chain drivers 20 and 22 are turned in a clockwise direction by the motion of the ratchet 16 and the worm 15 the trip 24 is

swung to the right by means of a connecting rod 27. The machine is so adjusted that the trip moves just far enough to disengage the release 30 when the desired bunch has been built on the base of the quill. The bunch builder chain 23 is connected to the ring-rail (not shown) of the spinning frame and imparts a short stroke, gradually raising the ring-rail until the trip 24 is released. The main builder chain 21 is also connected to the ring-rail and is engaged by the small driver 20 in such a manner that it releases the chain 21 more slowly than the chain 23. Chain 21 is so adjusted that it becomes right at the instant that chain 23 releases. Thus a longer stroke is imparted to the ring-rail and it is gradually lifted until the quills are filled.

The take-up rod 7 can be adjusted to different lengths by means of the turn buckle 10 and, therefore, the relative speed of the worm shaft to that of the spinning frame can be controlled. This allows the quills to be filled with yarn to any desired depth. As the roller 31 is adjustable longitudinally within its pivoted supporting arm 33 in which the slot 32 is formed, the bunch can be built of any desired length. The slot in the trip 24 allows the connecting rod to be adjusted relative to said trip 24 so as to cause the trip to release at a predetermined time during the operation of the device. Thus the depth of the bunch can be regulated.

What we claim is:

1. A bunch builder for spinning frames including a main builder chain, a bunch builder chain, simultaneously operating means for winding the chains at different

speeds, adjustable means for operating said chain actuating means at a speed proportioned to that of the spinning frame, a movably supported adjustably mounted roller engaging the bunch builder chain for adjusting the length of a bunch, a trip, a release adapted to be engaged thereby, and an adjustable operating means connected to the trip for controlling the depth of the bunch. 45

2. The combination with a counterbalanced body, a worm shaft, pawl and ratchet mechanism for operating the shaft and adjustable means for driving said mechanism from the spinning frame, of a worm gear driven by the worm shaft, driving drums of different diameters revoluble with the gear, 50 a main builder chain and a bunch builder chain connected to and actuated by the respective drums, a pivoted supporting member, a roller carried thereby and adjustable thereon for engaging the bunch builder chain, a release, a trip normally engaging the release, and an adjustable power transmitting connection between one of the drums and the trip for shifting said trip out of engagement with the release. 55

In testimony that we claim the foregoing as our own, we have hereto affixed our signatures in the presence of witnesses.

JESSE LEE ^{his} X LYLE.
